UNITED STATES PATENT OFFICE

2,613,761

AUXILIARY SPRING ATTACHMENT FOR
MOTION-PICTURE CAMERAS

Joseph J. Golick and Robert L. Moore, Chicago,
Ill., assignors to Revere Camera Company, Chi-
cago, Ill., a corporation of Delaware

Application July 29, 1949, Serial No. 107,416

7 Claims. (Cl. 185—40)

1

This invention relates to an auxiliary spring attachment for a motion picture camera.

Motion picture cameras designed primarily for amateur use ordinarily are driven by a single, self-contained coil spring. This spring has a winding key for manual winding. The film capacity of a usual camera of this type is so great that the spring must be wound several times during the course of exposing the film contained in a single loading.

It sometimes happens that the amateur user neglects to wind the spring at the proper times, with the result that the spring becomes exhausted during picture taking. When the spring thus runs down, camera action either slows down appreciably or stops entirely. In either case there is some film spoilage and, perhaps more important, the user fails to "get" the particular scene he is then taking.

Accordingly, one object of the invention is to provide an auxiliary attachment that contains springs of sufficient energy capacity to drive a camera for the length of time necessary to permit exposure of an entire loading of film. The attachment thus eliminates the possibility that the camera driving energy will become exhausted during picture taking, providing, of course, that the springs of the attachment are fully wound at the start.

Another object is to provide an attachment of this character that can be affixed to a camera in a facile manner. In brief, the camera does not have to be modified in any respect to receive the attachment. Further, the attachment may be applied and removed at will so that the camera can be used either with or without the attachment.

Another object is to provide an attachment that is readily usable with all makes of amateur motion picture cameras now commercially available. This is made possible by designing the attachment in such a manner that only a simple base member has to be changed in order to adapt the attachment to various different cameras.

Still another object of the invention is to provide a simple universal joint for transmitting spring stored energy from the attachment to the power train of the camera. A universal joint connection is necessary because there is likely to be a moderate misalignment between the rotatable axis of the attachment and the input to the power train of the camera.

Still another object is to provide an automatically operating brake that functions when the attachment either is applied to or removed from

2

the camera. Normally, when it is desired to remove the attachment from the camera, the springs in the attachment will not be completely run down. The automatically operating brake responds to a loosening of the bolt that secures the attachment to the camera, and thus, prior to separation of the attachment from the camera, the brake is applied to hold the springs against uncontrolled release. Conversely, when the attachment is affixed to the camera, the same securing bolt releases the brake after the attachment is connected to the camera through the above mentioned universal joint.

Another object is to provide a control on the attachment that actuates the starting and stopping control of the camera.

Other objects and advantages of the invention will be apparent as the description proceeds, reference being had to the accompanying drawings wherein one form of the invention is shown. It is to be understood that the description and drawings are illustrative only, and are not to be taken as limiting the invention except insofar as it is limited by the claims.

25 In the drawings:

Fig. 1 is a perspective view of a camera and the attachment of the invention showing in exploded manner the operative relation between the two units;

30 Fig. 2 is a sectional view through the attachment;

Fig. 3 is a sectional view on line 3—3 of Fig. 2 showing certain details of one form of universal joint;

35 Fig. 4 is a sectional view on line 4—4 of Fig. 2;

Fig. 5 is an end elevational view of the attachment looking from the right of Fig. 2;

Fig. 6 is a sectional view on line 6—6 of Fig. 2;

Fig. 7 is a fragmentary top view of the attachment;

40 Fig. 8 is a bottom view of the base member showing certain details of one form of brake;

Fig. 9 is a sectional view on line 9—9 of Fig. 8;

45 Figs. 10 and 11 show a modified form of universal joint and automatically operating brake that may be used in the attachment, Fig. 11 being a sectional view on line 11—11 of Fig. 10.

Referring now to the drawings, and particularly to Fig. 1, a typical amateur motion picture camera is shown at 15. The camera is driven by a single, self-contained coil spring (not shown) that is manually wound by winding key 16. A control for starting and stopping camera operation during picture taking is shown at 17.

50 55 The auxiliary spring attachment of the inven-

tion for this and other similar amateur motion picture cameras is shown at 20. The attachment, as will be seen, has a housing 21 that contains a plurality of series connected coil springs. A base member 22 is affixed to the bottom of housing 21 at one end. The base member 22 has a seat 23 of suitable size and shape to receive a portion of the bottom of the particular camera with which attachment 20 is used. The size and shape of seat 23 as well as the other geometry of base member 22 will vary depending upon the geometry of the camera. A special base member 22 is provided for each particular make of camera.

A bolt 24 extends through base member 22 and is received within the threaded tripod hole customarily provided in the bottom of camera 15. Bolt 24 is manually turned by knob 25 when attachment 20 is either secured to or removed from the camera.

Fig. 2 is a sectional view through the attachment showing the assembled relationship of the various component parts. It also shows the manner in which the attachment is connected to camera 15. Knob 25 may have a threaded hole for engagement with a tripod 26.

As mentioned, attachment 20 has a housing 21. The right hand end of the housing has a closure 27, while the left hand end has a closure 28, the two closures being provided with central openings that contain bushings 29 and 30, respectively.

Housing 21 contains a plurality of series connected coil springs. Three springs, 32, 33 and 34, are shown in the illustrated form of the invention. These springs are usually comparable in size, shape and energy capacity to the single, self-contained spring of camera 15.

Each spring is coiled about an individual hollow shaft or arbor, the arbors being indicated by 35, 36 and 37, respectively. The inner end of each spring is fixed to the respective arbor of that spring. The three arbors are coaxially aligned in end to end relation by means of a floating shaft 40. The right hand arbor, namely arbor 37, has an extension that is journaled in bushing 29. The left hand end of shaft 40 has an annular member 41 that is journaled in bushing 30. Thus each spring arbor is capable of rotation independently of the other spring arbors and annular member 41.

Each spring has a cup shaped case, the cases being respectively numbered 45, 46 and 47. The outer end of each spring is fixed to its respective case. As best shown in Fig. 2, spring case 47 is fixed at 49 to arbor 36 of the spring next to the left. Fig. 6 shows that arbor 36 is flattened on opposite sides at this point. The central opening in case 47 is likewise shaped so that the case and arbor rotate as one. Similarly, case 46 is fixed at 50 to arbor 35. The left hand case, namely case 45, is fixed at 51 to annular member 41.

Thus the three springs are inner-connected in series relationship, the energy from the springs being delivered by annular member 41. A universal joint mechanism, to be described later, transfers the spring stored energy from annular member 41 to winding key 16 of the camera.

Referring now to the right hand end of Fig. 2, Fig. 4 and Fig. 5, the spring winding arrangement of the attachment will now be described. The previously mentioned extension of arbor 37 carries an irregularly shaped end plate 54 that is rigidly fastened thereto by a bolt 55. A crank arm 56 is hinged at 57 to a peripheral point on

plate 54. Arm 56 is adapted to be pivoted outwardly from plate 54 to a limiting position normal to the axis of the attachment. The dotted lines show a position that arm 56 will go through in reaching the limit.

A crank handle shaft 58 is hinged at 59 to the free end of arm 56. A finger grip knob 60 is rotatably mounted on shaft 58. The shaft and knob fold outwardly to a limiting position as shown in the dotted lines to form a crank handle for convenience in operating the crank. The full lines in Fig. 2 show the manner in which the crank arrangement is folded within end plate 54 when not in use.

The extension of arbor 37 carries a ratchet 61a, best shown in Fig. 4. A pair of escapement pawl devices 61b and 61c cooperate with ratchet 61a to permit rotation of arbor 37 only in the proper direction for spring winding, i. e. clockwise in Fig. 4. Reverse rotation is prevented by the ratchet and the pawl devices. The pawl devices 61b and 61c are suitably mounted on closure 27 by rivets 61d and 61e, the closure having a moderate boss at each rivet.

Referring now to the left hand end of the attachment in Fig. 2 and Fig. 3, one form of universal joint that may be used in the attachment will now be described. Annular member 41 terminates in a threaded projection 62 (Fig. 2). A plate 63 is threaded on the projection in a rigid manner. Thus plate 63 rotates with annular member 41.

A pair of spaced, headed studs 64 and 65 are located on plate 63 at diametrically opposite points with respect to the circle of rotation described by plate 63. These studs pass through suitable apertures in an annular ring 67, the apertures being somewhat larger than the stud shanks so that annular ring 67 is freely tiltable with respect to plate 63. This annular ring forms an intermediate member in the universal joint.

Annular ring 67 has a protuberance or stud 68 located at a point remote from the ring center. This stud engages edge 69 of semi-disk member 70 of winding key 16 and drives the key as ring 67 rotates.

A leaf spring 72, best shown in Fig. 3, has one end attached to plate 63. The other end is attached to annular ring 67 immediately behind stud 68. Spring 72 is adapted to bias annular plate 67 so that stud 68 is in an extreme left hand position (referred to Fig. 2), the proper position for engagement with winding key 16.

As mentioned, there often is a moderate misalignment between the axis of the attachment (axis of annular member 41) and the axis of winding key 16. The above described universal joint functions to transmit rotary motion regardless of such misalignment. It is apparent that any misalignment is compensated for by the tilting action of annular ring 67 with respect to plate 63 and by the ability of stud 68 to slide radially along the edge 69 of semi-disk 70. Furthermore, this type of universal joint including protuberance 68 establishes a connection between the attachment and various cameras despite slight differences in winding key sizes and shapes.

A modified form of universal joint means will be described later.

In addition to the drive connection provided by the above described universal joint, the attachment is physically connected to the camera by base member 22. The attachment housing 21

is rigidly connected to base member 22 by suitable means such as screws 75 (Fig. 8). The left hand portion of base member 22 has the previously mentioned seat 23 to receive camera 15. The bolt 24 having knob 25 is adapted to pass through a suitably located aperture in member 22 and be received within the threaded tripod hole 76 (Fig. 2) of the camera bottom. As also previously mentioned, the size and shape of seat 23, as well as the location of the aperture for bolt 24, are governed by the particular camera with which base member 22 is to be used. In other words, there will be an individual base member designed for each of the various cameras to which the attachment is adapted.

Because of the fact that the attachment may sometimes be removed from its associated camera while there is still some energy stored in the attachment springs, it is desirable to provide an automatically operating brake so that the springs will not abruptly exhaust themselves when stud 68 is no longer in engagement with winding key 16. One form of brake, that shown in Figs. 2, 8 and 9, will now be described. Fig. 2 shows the brake in released position, while Fig. 9 shows the brake in applied position.

Referring first to Fig. 2, the active braking element is a friction member 80 that is adapted to bear against case 45 of spring 32, the last spring of the series of springs. As case 45 is rigidly connected to annular member 41, it will be seen that the brake thus controls the energy output element of the attachment, i. e. member 41.

Friction member 80 is carried at one end of a lever 82 (sometimes called a friction member carrier), the lever being slightly bent intermediate its ends to provide a pivot surface 83 that bears on the bottom of base member 22. The other end of lever 82 has an aperture 84 through which passes the shank of bolt 24. The bolt shank has a flange 85 that engages the bottom surface of the lever end around the aperture 84.

Lever 82 has an aperture 87 intermediate pivot surface 83 and friction member 80. This aperture receives a reduced diameter, headed bolt 88 that is threaded through base member 22 and into the wall of housing 21. A relatively stiff spiral spring 90 extends between the head of bolt 88 and lever 82, as clearly shown in Figs. 2 and 9. This spring exerts sufficient pressure against lever 82 so that friction member 80 is able to hold spring case 45 against rotation despite the energy stored in springs 32, 33 and 34. As seen in Fig. 9, spiral spring 90 is effective to apply the brake when bolt 24 is not in engagement with tripod hole 76 of the camera. In this circumstance, the attachment has been physically separated from the camera.

The brake is so designed that engagement of the attachment with the camera must be substantially completed before the brake is released. To this end the shank of bolt 24 is sufficiently long to be substantially threaded into tripod hole 76 of the camera before flange 85 exerts pressure on lever 82. After flange 85 engages the lever, further turning of knob 25 causes lever 82 to pivot about 83 with the result that spring 90 is compressed and friction member 80 is separated from case 45, thus releasing the brake. Release of the brake at this point, however, is not objectionable because stud 68 of the universal joint is then already in position to engage the winding key. It might be that annular ring 67 will rotate a portion of one turn as the brake is released, but

it will rotate no farther due to engagement of stud 68 with winding key edge 69.

Conversely, when the attachment is separated from the camera, the brake will be applied before bolt 24 can be removed from the camera, thereby making it impossible to disconnect the universal joint before the brake is set by spring 90.

Another form of automatically operating brake will be described later.

10 It will be noted in Fig. 2 that the camera starting and stopping control 17 is rendered more or less inaccessible when the attachment is properly positioned with respect to camera 15. Accordingly, means are provided on the attachment for actuating camera control 17.

15 An elongated boss 93 is provided on the top of the attachment. The right hand end of boss 93 (Figs. 2 and 6) is recessed as shown at 94. Also, a central opening is provided throughout the 20 length of boss 93.

25 A shaft 95 extends through the central opening from one end of the boss to the other. At its left hand end (Fig. 2), shaft 95 is bent at right angles as shown at 96, the free end of the bent portion terminating in operative relation with camera control 17. A plate 97 (Figs. 2, 6 and 7) is rigidly secured to shaft 95 within recess 94, the plate size being such that it can be rotated within the recess an amount sufficient to bring shaft portion 96 into and out of effective engagement with camera control 17. As camera control 17 is normally spring biased to "off" position, it is usually not necessary to bias shaft 95 and plate 97, the bias of control 17 being sufficient to rotate shaft 95 away from camera operating position.

30 As will be understood, in order to start camera operation, the user merely depresses the proper side of plate 97. This rotates shaft 95 and causes portion 96 to move camera control 17 to operating position. The user keeps plate 97 depressed as long as camera operation is desired, after which plate 97 is released so that the bias of control 17 can stop camera operation.

35 Referring now to Figs. 10 and 11, modified forms of universal joint and automatically operating brake will now be described. Spring arbors 100, 101 and 102 (Fig. 10) are provided with enlarged central openings. The central opening in arbor 102 may be reduced at its right hand end as shown at 103.

40 A shaft 105, hollow in part, is received within the arbor openings. Case 106 of the left hand spring is fixed at 107 near the left end of shaft 105. Thus energy from all the springs is coupled to shaft 105, the shaft in this respect corresponding with annular member 41, previously described.

45 The hollow opening in shaft 105 terminates in a reduced portion 109 that is non-circular in cross section, for example square. Received within the hollow opening of shaft 105 is a shaft 110 that has an end portion 111 corresponding generally in section with the shape of non-circular hollow portion 109. Thus end portion 111 of shaft 110 may be square in section, but its dimensions should be slightly smaller than the dimensions of hollow portion 109 so that shaft 110 is free to wobble with respect to shaft 105. However, the respective dimensions should be close enough so that a driving relationship is established.

50 A spiral spring 113 may be provided to urge shaft 110 to the left.

55 The left hand end of shaft 110, which is likewise non-circular in cross section, loosely receives a hollow sleeve 115. The opening in this sleeve, while larger than the end of shaft 110, has the

same non-circular shape so that a wobble drive relationship is established. The exterior of sleeve 115 is threaded to receive a camera winding key engaging member 116. Since various cameras have differently shaped winding keys, a special key engaging member 116 is provided depending upon the particular camera with which the attachment is to be used. The illustrated member 116 is designed to engage the winding key 16 of the camera illustrated in Fig. 1.

Sleeve 115 has an annular flange 118 that together with member 116 defines an annular channel. A bracket 120 has an enlarged central opening 121 through which passes a portion of member 116. The central opening 121 of bracket 120 is sufficiently small so that the bracket functions as a keeper for the assembly consisting of sleeve 115 with its annular flange 118 and key engaging member 116. Opening 121, however, is sufficiently large to permit eccentric rotation of member 116.

As will be understood, the various wobble drive connections provide a universal joint between shaft 105 (the driving element) and member 116 and its associated winding key (the driven elements). As mentioned, member 116 is readily interchangeable with other members 116 so that the attachment can easily be adapted to any particular make of camera.

The modified automatically operating brake illustrated in Figs. 10 and 11 is of the pawl and ratchet type. A ratchet 125 is rigidly mounted near the left hand end of shaft 105. A pawl 126 is pivoted at 127 in operative relation to ratchet 125. A spring 128 (Fig. 11) biases pawl 126 to ratchet engaging position. The spring 128 is omitted in Fig. 10 for clarity.

Pawl 126 is actuated by a link 130 connected to one end of a lever 131 (Fig. 10). The lever is bent intermediate its ends to provide a pivot surface, and it has an aperture in the region of the bend. The aperture receives a reduced diameter, headed bolt 132 that is threaded into the bottom of base member 133. The base member 133 corresponds generally with the base member 22 previously described.

A second aperture is provided in lever 131 near the end opposite to that connected to link 130. This second aperture is generally aligned with an aperture in base member 133. A threaded bolt 135 having a knob 136 passes through the last mentioned two apertures and is adapted to be received within the threaded tripod hole in the bottom of camera 15. Insertion and withdrawal of bolt 135 causes coaction between knob 136 and lever 131. The lever thus rocks about its bend, and this motion is transmitted through link 130 to pawl 126.

When the attachment is separate from the camera, bias spring 128 maintains pawl and ratchet engagement, thus preventing escape of spring stored energy. When the attachment is connected to the camera through the universal joint, and bolt 135 is partially received within the tripod hole, continued threading of the bolt rocks lever 131 at the bend to release pawl 126 from the ratchet. Escape of spring energy is then limited by the universal joint connection.

It will be understood that the series connected springs of the attachment are, through the universal joint, connected in series with the single, self-contained spring of the camera. Thus, if the attachment contains three springs, the amount of energy available for driving the camera is that of four springs. It has been found that the

energy of four fully wound springs is sufficient to drive a camera for the proper length of time to expose all the film contained in a single loading. Consequently, if the springs are properly wound at the outset, there is no danger that the springs will unexpectedly run down while pictures are being taken.

From the above description it is thought that the construction and advantages of our invention will be readily apparent to those skilled in the art. Various changes and modifications may be made without departing from the spirit or losing the advantages of the invention.

Having thus described our invention, what we claim as new and desire to secure by Letters Patent is:

1. An auxiliary spring attachment for a motion picture camera comprising a housing, a plurality of series connected coil springs within said housing, means for winding said springs, a universal joint for transferring energy from said springs to the winding key of said camera, said universal joint including a shaft rotatable by said springs, a plate fixed to said shaft, a pair of spaced studs on said plate, an annular ring carried by said studs in tiltable relation with said plate and a key engaging stud on said ring, a base member extending from said housing, a bolt through said base member for engagement with the threaded tripod hole of said camera, and a brake cooperating with said bolt, said brake being operative to prevent release of spring energy except when the attachment is mounted on said camera.

2. An auxiliary spring attachment for a motion picture camera having a winding key, said attachment comprising a housing, spring means within said housing, a manually operated member for winding said spring means, means for transferring energy from said spring means to the winding key of said camera, a brake to prevent escape of spring stored energy except when the attachment is secured to a camera, and means for securing the attachment to a camera, said means cooperating to release said brake when the attachment is secured to a camera.

3. A safety brake for an auxiliary spring attachment for a motion picture camera, said attachment having a series of inter-connected coil springs each enclosed in a case which is driven by its respective spring, said brake comprising a friction member adapted to engage and fix against rotation the case of the last spring of the series, a lever pivoted intermediate its ends, said friction member being mounted at one of the lever ends, a relatively stiff spring cooperating with said lever to urge said friction member into braking contact with said case, the other lever end being engaged by a bolt that secures the attachment to a camera whereby bolt action overcomes said spring and releases said brake when the attachment is affixed to a camera.

4. A safety brake for an auxiliary spring attachment for a motion picture camera, said attachment having a series of inter-connected coil springs each enclosed in a case which is driven by its respective spring, said brake comprising a friction member adapted to engage and fix against rotation the case of the last spring of the series, a friction member carrier that is movable toward and away from said last spring case, said carrier being spring biased whereby said friction member is urged into braking relation with said case, and means for releasing said

brake when said attachment is secured to a camera.

5. In an auxiliary spring attachment adapted to be secured to a spring driven motion picture camera by a bolt threaded into the tripod hole of the camera, a safety brake for preventing the escape of spring stored energy except when said attachment is secured to the camera, said brake including a spring biased brake element for engagement with a driving member of the attachment, and means coacting with said securing bolt to disengage said brake element when said bolt is tightened to attachment securing position.

6. In an auxiliary spring attachment adapted to be secured to a spring driven motion picture camera by a bolt threaded into the tripod hole of the camera, a safety brake for preventing the escape of spring stored energy except when said attachment is secured to the camera, said brake including a ratchet fixed to a driving member of the attachment, a pawl spring biased into engagement with said ratchet to prevent ratchet rotation in spring unwinding direction, means interconnecting said pawl with said securing bolt whereby tightening said bolt within said tripod hole effects disengagement of said pawl with said ratchet to release the brake.

7. An auxiliary spring attachment for an amateur type motion picture camera that has a self-contained spring motor, a start-stop control, and a spring winding key; said spring attachment comprising a housing, a plurality of axially

5
10

aligned coil springs within said housing, the springs being series connected, means for winding said springs, a universal joint connecting one of said springs with the winding key of a camera, a base member extending from said housing, means on said base member for removably connecting said attachment to a camera, a brake means for said springs, and a brake means actuating lever in said base member, said lever being movable to release said brake means when said attachment is connected to a camera.
